UNITED STATES PATENT OFFICE

INGRID ELISABETH AKESSON, OF BOSTON, MASSACHUSETTS

SANITARY SHIELD FOR TOILET SEATS

Application filed January 23, 1930. Serial No. 422,778.

This invention relates to sanitary shields or protective covers for toilet seats or the like, and the principal object of the invention is to provide an improved paper protector of this character which is simple and economical to manufacture, which may be folded into a compact package for dispensation in envelopes at public washrooms, and which may be conveniently used to ensure cleanliness and 10 to protect the person from possible infection.

More specifically, the invention contemplates the provision of a paper shield to rest upon and completely cover a toilet seat, and having its side margin shaped to overhang 15 the periphery of the seat to prevent the shield from slipping therefrom.

A preferred embodiment of the invention is illustrated in the accompanying drawings, in which:

20 Fig. 1 is a side elevation of a toilet seat equipped with the improved shield;

Fig. 2 is a plan view of the shield in a flat state, prior to the formation of the depending sides; and

25 Fig. 3 is a side elevation of the shield having the preformed depending margins.

The shield is formed of suitable flexible sheet material, such as crepe or tissue paper cut in appropriate contour to provide a generally rectangular portion 4 having a central opening 5, and a projecting tab portion 6 at one end provided with longitudinal and transverse lines of perforations 7 and 8 to form detachable rectangular sheets 9 and 10.

30 The seat portion 4 has diagonal slits 11 cut inwardly from its rounded corners, and the divided corner portions are then overlapped and cemented together as indicated at 12 to provide depending sides 13.

When applied upon the toilet seat 14, the seat portion 4 covers the top of the seat 14, and the side margins 13 overhang the sides of the seat and tend to hold the shield in proper position and prevent displacement thereof. The tab 6 preferably projects forwardly of the seat 14 so that the individual sheets 9 and 10 may readily be torn off by the user. It is obvious that the tab 6 may be subdivided into any reasonable number of 45 detachable sheets by proper lines of perfora-

tions, depending upon the dimensions of the tab and desired size of the detachable sheets.

It is apparent that a protective shield constructed as above described may be manufactured at small cost and may be readily folded 55 into small compass for dispensation in individual envelopes or in vending machines. The shield is convenient to use and provides readily accessible, removable sheets of toilet tissue, so that a person equipped with the improved protector need not necessarily rely upon an available supply of tissue at the washroom. The protectors are, of course, destroyed after use and may be flushed down 60 the seat without clogging the drainage system.

I claim:

1. A shield for toilet seats formed of a sheet of paper having slits at its sides extending inwardly from its periphery, the edges 70 of the slitted portions being overlapped and cemented together to furnish depending side margins adapted to overhang the sides of the seat thereby to prevent displacement of the shield.

2. A shield for toilet seats comprising a seat portion of regular contour formed of a sheet of paper and generally rectangular in outline, the corners of the seat portion being rounded and having diagonal slits extending inwardly from the periphery thereof, the opposed margins of the slitted portions being overlapped and cemented together to furnish depending sides adapted to overhang the toilet seat thereby to prevent displacement of the shield.

Signed by me at Boston, Massachusetts, this 21st day of January, 1930.

INGRID ELISABETH AKESSON.
